UNITED STATES PATENT OFFICE.

ROBERT P. BUSHMAN, OF EAST ORANGE, AND EDWARD L. BUSHMAN, OF SOUTH ORANGE, NEW JERSEY, AND NATHAN M. FEENEY, OF IOLA, KANSAS, ASSIGNEES, BY MESNE ASSIGNMENTS, TO BATES VALVE BAG CORPORATION, OF CHICAGO, ILLINOIS, A CORPORATION OF NEW JERSEY.

BAG-FILLING MACHINE.

Application filed August 29, 1924, Serial No. 735,001. Renewed May 23, 1928.

This invention relates to bag filling and weighing machines with special reference to types in which finely powdered or granular material, such as cement, is deposited in definite quantities by weight, into bags having a relatively small lateral opening at their upper ends commonly known as valve bags. In this type of machine the bag is supported near a discharge throat in such a manner that the bag valve is in position to receive material from the discharge throat through which material is forcibly fed from the hopper to the bag. The valve bag and its support are adapted to be moved with respect to the discharge throat; and suitable portions carried respectively by a movable part and a stationary part of the machine are in sliding engagement and are adapted to act as a seal to prevent the leakage of cement between these parts. These engaging portions are therefore subjected to a deposit of the cement as it is fed into the bag with great force. This tends to hinder the free movement of these parts, due to the clogging effect of such material, which is gritty and compactable.

An object of this invention is to provide an efficient and effective means to prevent the filling material from hindering the free movement of the relatively movable engaging parts which are subjected to the filling material as it is fed into the bag.

Other objects of the invention are to provide a pivoted delivery spout actuated automatically upon completion of the filling operation to positively close the inlet passage in a substantially frictionless manner, and manually operated auxiliary means for preventing flow until an empty bag has been substituted for that previously filled.

The action of the automatic cut-off is dependent upon the operation of a compound weighing device comprised of a platform scale carried on a pair of parallel levers mounted one above the other on knife-edge pivots and capable of being accurately adjusted by counterpoises to the predetermined weight of material to be entered in each bag, thus tending to economy, speed, and convenience in handling.

The delivery spout is flared to facilitate delivery and prevent possible clogging, and

adjusting devices are supplied at all desirable points.

The invention consists in the novel features of construction, arrangement and combination of parts embodied, by way of example, in the apparatus hereinafter described as illustrating the preferred form of the invention, and the invention will be more particularly pointed out in the appended claims.

Further objects and advantages of the invention will more fully appear from the following description taken in connection with the accompanying drawings which show, by way of example, the preferred embodiment of the invention.

Referring to the accompanying drawings, in which the same reference characters indicate the same parts in the various views:

Figure 1 is a side elevational view of one embodiment of the invention, illustrating its use.

Figure 2 is a partial front elevational view of one scale unit, the bag being removed.

Figure 3 is a fragmentary longitudinal sectional view of one form of the delivery spout and valve, taken on the center line and drawn to an enlarged scale.

Figure 4 is a top plan view of the same.

Figure 5 is a view similar to Figure 3, but showing the spout inclined and the valve closed.

Figure 6 is a side elevational view, similar to Figure 1, but showing a modified form of construction.

Figure 7 is a front view thereof.

Figure 8 is an enlarged fragmentary vertical sectional view of the spout used in the structure shown in Figure 6, the passage being open.

Figure 9 is a horizontal sectional view of the same.

Figure 10 is a vertical sectional view, similar to Figure 8, but showing the passage closed.

Figure 11 is a perspective view of a spout used in connection with open topped bags and interchangeable with the other form of spout in the machine.

Figure 12 is a fragmentary sectional view similar to Figure 8 but slightly modified therefrom, showing the cut-off in detail.

Figure 13 is a fragmentary side view similar to Figure 6, and showing means for retaining a bag upon the discharge spout until released.

5 Machines for the purpose outlined are usually composed of a series of units, disposed in parallel spaced relation upon a common base or foundation, supplied from a single feed trough and actuated by a 10 power-driven shaft.

The preferred type of such machine as shown in Figures 1 and 2 of the drawings, consists of side frames, generally denoted by the numeral 20, composed of bases 21 15 having forwardly extending elements and raised columns, convergently inclined at their upper ends.

Connecting between pairs of these frames, at their bases, are the members, as the rolled 20 beams 22, held rigidly by riveted angles 23, and at the front by a cross beam 24 having flanged ends 25 also riveted to the frames.

The frames are further held in rigid relation at their upper converging ends by 25 being secured to the bottom of a feed trough 26 into which the material is supplied in any convenient manner.

30 Openings 27 in the feed trough, controlled by gate valves 28 lead to hoppers 29 having converging side walls in which is revolvably mounted a shaft 30, driving an impeller (not shown) used to agitate and force the material forward to the outlet, indicated by the flange 31, to which is secured a hollow, 35 elbow-like valve connection 32.

A bracket 33 is fixed on the upper horizontal face of the beam 22, the bracket having an upright extension 34. Bifurcated bosses 35 on the brackets and similar bosses 40 36 on the extensions are formed with open topped, V shaped seats or recesses to receive knife-edge elements 37 and 38 set respectively in levers 39 and 40, relatively lower and upper, at about the center of their 45 lengths.

These levers extend centrally between the frame sides, from near their rear columns to points substantially in a vertical plane with the bar, 24, and are connected in parallel by a pivoted yoke 41 at their rear ends.

The lower lever 39 has slidably mounted on it a weight 42 of considerable magnitude, a corresponding but lighter weight 43 being adjustable on the upper lever 40 and provided with a thumb-screw 44 engageable with teeth 45 on the upper edge of the lever, when the weights are in adjusted positions relative to the weight of material to be filled into a single bag.

60 The forwardly extending ends of the levers 39 and 40 are forked and provided with openings 47 and 48 to receive knife-edge elements 49 and 50 fixed in a bar 46, constrained to move in a vertical plane due 65 to the double lever and link connection.

A pad 51 at the bottom of the bar 46 contacts with the seat 52 carried on a support 53 integral with the cross beam 24, forming a solid abutment to receive the impact of the bar 46 upon its descent.

Carried at the upper end of the bar 46 is a ribbed plate 54 on which rests the base 55 of a scale having a platform 56 to which is attached a rearwardly reaching arm 57 carrying the stem 58 of a forked yoke 75 59 pivotally supporting a curved apron or guide plate 60 adapted to position a receptacle, as the bag 61, centrally on the platform 56 and partially supporting the bag as it becomes filled.

80 The upright 62 (Fig. 2) of the platform scale frame is secured to lugs 63 of the base 55 and its horizontal arm 64 is provided with a graduated scale beam 65 and adjustable weight 66 by which the load on the platform 54 may be accurately determined.

85 Returning now to the valve connection 32, it will be seen in Figures 1, 3, 4, and 5 that its outer flange is disposed in a perpendicular plane, facing the front of the machine, 90 and attached to it is a rectangular valve body 70 having a smoothly finished concave face 71, the axis of which is in a horizontal plane.

95 Rigidly fixed on opposite sides of the valve body 70 or discharge throat are forwardly extending arms 72 and 73 having in-reaching hubs at their ends, the arm 72 carrying a set-screw 75 and the opposite arm having journaled in it a spindle 76.

100 The point of the set-screw 75 and inner end of the spindle bear upon bosses 77 fixed on opposite sides of a spout 78, at its cylindrical end adjacent the discharge throat 70, the outer portion of the spout being preferably flared or expanded at its under side 79, and cut angularly, as at 80 from a point in the flared portion to the opposite upper side, presenting a thin narrow entering end 81 (Fig. 2) suited to readily enter an opening in the upper edge of the bag the shape of the discharge opening being ovoidal and of greater area than the inlet opening of the spout.

105 The spout 79 when so entered in the opening of the bag 61 serves to support the bag by the top thereof; a part of the load being also carried, when the bag is filled, by the platform 56.

110 The spout 78 is swung upon the axis of the spindle 76, by means of an arm 82 fixed to the spindle and pivotally engaged at its outer end by a rod 83, connected by a turn-buckle 84 with the rod 85 pivoted to a bracket 86 fixed on the side of the platform 56, opposite the scale upright 62.

115 From the foregoing it will be seen that when the platform 54 is in a raised position, the spout 78 will be held substantially horizontal, but when the platform is lowered, the spout will be swung upon its pivots into 120

the position shown in broken lines in Figure 1 or as indicated in Figure 5.

It is therefore obvious that, since the top of the spout 79 is in supporting engagement 5 with the upper lip of the bag 61, as the spout is moved to a downwardly inclined position as shown in dotted lines in Fig. 1 (and as shown also in Fig. 5) the downward force of the filled bag will cause the bag 10 to slide forward and downwardly along the spout 79.

A flat bar 87 (Figs. 3 and 5) is disposed horizontally across the center of the opening in the valve body 70, the front face of 15 the bar containing a concave recess 88 presenting sharply defined lateral wiping edges and similar recesses 89 are formed in the concave face of the valve body above and below the bar 87.

20 Fixed on the end of the spout 78 is a band or heavy ring 90 formed on a convex head 91, suited to closely engage and partially rotate against the concave face 71 of the discharge throat on the axis 76.

25 This head 91 has a transverse bar 92 across its center, corresponding to the bar 87 of the discharge throat, and like it, being concavely recessed as at 93, other recesses 94 being formed in the head in parallel 30 planes.

Thus when the spout 78 is extended horizontally, as best shown in Figure 3, the openings 95 in the discharge throat 70 will register with the similar openings 96 in the head 35 91, permitting powdered or granular material to flow freely from the hopper 29 through the throat and out at the end of the spout 78, provided the gate valve 28 is open.

Contrariwise, when the spout 78 is inclined 40 downwardly, as shown in Figure 5, due to the weight of material entered into the bag 61, tilting the scale levers 39 and 40, the passages 95 in the discharge throat are closed by the valve head and no material can flow outward.

The purpose of the recesses 88 and 89 in the valve body and the similar recesses 93 and 94 in the head 91, is to reduce friction, thereby rendering the device highly sensitive and for the further purpose of presenting relatively sharp scraping edges at opposed surfaces tending to remove any accumulations and prevent clogging during their relative movement, in a manner that 55 will be readily understood.

In operation, an empty bag is placed on the platform 56 adjacent the apron 60, and the spout 78 inserted in a small side opening in the bag which is partially sustained 60 by the spout.

Upon opening the gate valve 28 material will flow directly into the bag until the weights 42 and 43 are overcome, thus lowering the plate 54 and inclining the spout, 65 shutting off further flow and simultaneous-

ly allowing the filled bag to slide downwardly and off the spout 78. The gate valve 28 may, then be closed, the filled bag removed from the platform 56, and another empty bag substituted, the spout and platform rising immediately upon the removal of the filled bag, the weight of which can be ascertained and checked by the reading of the scale beam 65.

Figures 6 and 10 inclusive illustrate a 75 modified machine for accomplishing the same purpose, which will now be described.

In this adaptation the frames are generally denoted by the numeral 100, the same being arranged in pairs connected at the 80 front and rear by channels 101 and an I beam 102 at the center.

Fixed on the beam 102 are brackets 103 having seats for the knife-edge elements 104 and 105 secured respectively in pairs of 85 levers 106 and 107, the same being pivotally connected at their rear ends by a bar 108 having a rigid horizontal arm 109 on which is adjustably mounted a weight 110.

The front extending ends of the levers 106 90 and 107 contain openings to receive reversed knife-edge elements 111 and 112 in bars 113 rigidly connected by an angle plate 114, the vertical member of which is riveted to upright bars 115.

The upper ends of the bars 115 are coupled by a rigid yoke 116 having fixed on its face a bracket 117, shaped to present a socket 118 (Fig. 8) formed by the undercut, convergingly inclined walls 119 open at the 100 top and throughout its main front portion.

Engageable in the socket 117 is a trapezoidal block 120 having a forwardly extending hub 121, the block and hub being bored to receive a spout 122, having a downwardly 105 inclined lower portion 123 (Fig. 6) and cut angularly therefrom, as at 124, to the slightly down-curved point 125. The collar 121 is provided with a set screw 126 to secure the block upon the spout. For use in connection with open topped bags a spout 127 is substituted, the same being fixed at its downturned delivery end, in a rectangular plate 128, (see Figure 11) suited to enter the bag, it being understood that the blocks 110 120 are alike and interchangeable in all cases.

The face of discharge throat 138 is recessed to receive a shutter plate 129, the same having an opening 130 normally in 120 register with the opening 131 in the yoke and which, when the filling operation is proceeding, is in register with the opening in the spout 122, providing a clear and uninterrupted passage.

The shutter plate 129 is operated by a pivoted hand lever 132 as shown in Figure 7, thus providing means for manually controlling the passage leading to the spout.

As in the preceding description, a feed 130

trough 134, common to all the hoppers 135, is fixed at the top of the frames 100, the hoppers being provided with suitable impellers driven by the shaft 136 and having an angularly disposed discharge 137 engaged with a horizontal discharge throat 138.

The forwardly extending flanged portion 138^a (Fig. 8) of the throat 138 is arranged adjacent the yoke 116 and secured to the 10 face of the throat 138 is a collar 139 having a sharply defined bevelled outer edge adapted to barely clear the surface of the yoke 116 as the latter is moved up and down relatively to it, making an efficient cut-off. In place 15 of a separate ring 139, the outer surface of the discharge throat may be shaped to present a bevelled annulus 138^b, as shown in Figure 12, the edge of the annulus being adjusted closely to the rear surface of the yoke 20 as before described.

Fixed to the upper end of the yoke 116 is a guide rod 140 slidably engaging a bracket 141 fixed to any stationary part of the machine, as the feed trough 134, its purpose 25 being to steady the yoke in its movements and maintain it against the edge of the wiping collar 139.

Secured to the bars 115, near their lower ends, is a concave seat 142 receptive of a bag 30 during the filling operation, this seat having a supporting portion 143 against which the side of the bag may rest, the upper end of the bag being supported directly by the spout 122 which is entered therein.

The operation of this modified form of machine is substantially the same as that of the foregoing, except that in place of the spout inclining when the scale beams oscillate, the spout is moved bodily downward, 35 this action closing the passage, as best shown in Figure 10, to the flow of material automatically, with a minimum of friction due to the shape of the cut-off collar 139. Means for retaining a bag on the spout are shown 40 in Figure 13, in which a bracket 145 is secured to the hopper 134 and pivoted to the hub 146 of the bracket is an arm 147 rocked by the handle 132. The downturned forward end of the arm engages a hook 148 connecting with the device 149, pivoted on a pin 150 to the rear end of a dog 151 having teeth or serrations on its under surface, pressed by 45 a weight 152 to rest upon the fabric of the bag 61 as supported on the spout 122.

The dog 151 is pivoted on an arm 153 carried by a bracket fixed on the spout and moved with it up and down, the hook 148 being shaped to permit of such movement without raising the dog from the bag, this 50 being accomplished when the filled bag has moved down and the shutter closing lever 132 manually operated.

Having thus described our invention with particularity with reference to the preferred 55 embodiment of the same, and having re-

ferred to some of the possible modifications thereof, it will be obvious to those skilled in the art after understanding our invention, that other changes and modifications may be made therein without departing from the 70 spirit and scope of the invention, and we aim in the appended claims to cover such changes and modifications as are within the scope of the invention.

We claim—

1. In a valve bag filling machine, the combination of feeding means having a discharge throat, a scale having a movable part for weighing material fed to the bag, means movable with said movable part of the scale 80 and having provision for supporting the bag with its valved opening in position to receive material from said discharge throat, said feeding means and said movable means being provided with opposed engaging portions adjacent to said discharge throat, and at least one of said opposed engaging portions being provided with a sharply defined scraping edge for engaging the other portion. 85

2. In a valve bag filling machine, the combination of feeding means having a discharge throat, a scale having a movable part for weighing material fed to the bag, a substantially horizontal valve bag filling spout 90 normally in register with said throat and movable with the scale and adapted to project into the valved bag, said feeding means adjacent the throat and said spout being provided with opposed engaging portions, and at least one of said opposed engaging portions being provided with a sharply defined scraping edge for engaging the other portion. 95

3. In a valve bag filling machine, the combination of a discharge throat having a discharge opening and provided with a bearing surface, and a filling spout movable relative thereto having an opening normally registering with said discharge opening and provided with a bearing surface in slidably engagement with said throat bearing surface, one of said surfaces having a sharply defined scraping edge, and said surfaces being adapted when cooperatively moved one with 110 respect to the other to close one of said openings. 115

4. In a valve bag filling machine, the combination of a discharge throat provided with an opening, a filling spout provided with 120 an opening in register with said throat opening, and a relatively fixed cut-off portion and a relatively movable cut-off portion provided with cooperating faces adapted to close one of said openings, one of said faces 125 having a sharply defined scraping edge in sliding engagement with the other of said faces, and means to move said engaging faces one with respect to the other whereby said opening will be closed. 130

5. In a valve bag filling machine, the combination of a discharge throat provided with a discharge opening, a valve bag filling spout provided with an opening normally in register with said throat opening, cut-off means for closing one of said openings comprising a smooth face portion and a sharply defined scraping portion in intimate sliding engagement and movable one 10 with respect to the other, thereby reducing to a minimum the interference of material being fed into the bag with the free relative movement of said sliding parts.
6. In a valve bag filling machine, a tubular discharge spout having a downwardly inclined lower wall and cut diagonally from a point midway in the length of said lower wall to the extreme end of the opposite wall.
7. The combination in a valve bag filling machine having a discharge throat, a spout cooperating therewith, automatic means for 15 cutting off the flow from the discharge throat when the spout is out of register therewith, and manual means for cutting off the supply from said discharge throat, 25 of means to clamp the bag to be filled to said spout, said clamping means being released only upon operation of the manual cut-off.
8. In a valve bag filling machine, a rigid discharge throat and a spout engaged therewith, said spout having a constantly increasing cross-sectional area.
9. In a valve bag filling machine, a tubular discharge spout having a substantially horizontal upper wall and a downwardly inclined lower wall, said lower wall being cut diagonally from a point midway in the length of said lower wall to the extreme end of the opposite wall.
